COMBINED JUICER AND MIXER

Opal G. Hooe, Visalia, Calif.

Application May 18, 1953, Serial No. 25,077

Term of patent 14 years

(Cl. D44—1)

To all whom it may concern:

Be it known that I, Opal G. Hooe, a citizen of the United States of America, residing in the city of Visalia, in the county of Tulare, State of California, have invented a new, original, and ornamental Design for a Combined Juicer and Mixer, of which the following is a specification, reference being had to the accompanying drawing, forming a part thereof.

Figure 1 is a perspective view of a combined juicer and mixer, in position to be used as a mixer, showing my new design;

Figure 2 is a perspective view of said combined juicer and mixer in position to be used as a juicer with the cap portion removed; and

Figure 3 is a fragmentary, vertical sectional view taken on line 3—3 of Figure 1.

I claim:

The ornamental design for a combined juicer and mixer, substantially as shown and described.
